FIREARM OR THE LIKE

Melvin M. Johnson, Jr., New Haven, Conn., assignor to Advanced Developments, Inc., New Haven, Conn., a corporation of Connecticut

Filed June 8, 1962, Ser. No. 70,470

Term of patent 3½ years

(Cl. D30—1)

Fig. 1

Fig. 2

Fig. 4

FIG. 1 is a side elevation of a firearm showing my new design;

FIG. 2 is a plan view;

FIG. 3 is a front end view; and

FIG. 4 is a rear end view.

The undisclosed side of the firearm is substantially the same in appearance as the side shown.

I claim:

The ornamental design for a firearm or the like, substantially as shown and described.
